UNITED STATES PATENT OFFICE.

ABBIE E. GREVES, OF BROOKLYN, NEW YORK.

SCHOLAR'S COMPANION.

SPECIFICATION forming part of Letters Patent No. 539,682, dated May 21, 1895.

Application filed September 27, 1894. Serial No. 524,255. (No model.)

To all whom it may concern:

Be it known that ABBIE E. GREVES, a citizen of the United States, residing at Brooklyn, in the county of Kings and State of New York, have invented certain new and useful Improvements in Scholars' Companions; and I do hereby declare the following to be a full, clear, and exact description of the invention, such as will enable others skilled in the art to which it appertains to make and use the same.

This invention has relation to improvements in scholars' companions and it consists in the construction and arrangement of parts as will be hereinafter described and particularly pointed out in the claim.

The annexed drawings, to which reference is made, fully illustrate my invention, in which—

Figure 1 represents a face view of my device. Fig. 2 is a vertical cross-sectional view of the same folded. Fig. 3 is a side view, and Fig. 4 is a back or rear view.

Referring by letter to the accompanying drawings, A designates the scholar's companion or hand receptacle composed of a double thickness of water proof material as at *a a* and which are stitched to one another around the edges having the binding of tape secured thereto as shown at *b*. On the inner face of the inner piece of material is arranged an elastic strip *c* which passes through slits *d* made in the said inner face and the ends *e, e* thereof are stitched to the companion as shown. This elastic piece provides a rack or secure for pencils, pen holders, slate pencils, &c., while the ends of the same project into slits or openings *f* made in the inner face of the device and prevent the pencils, &c., from being lost or accidentally displaced from said elastic holder.

C, represents a piece of water proof material arranged about the center of the device and extends from one side thereof to the other side and is stitched at its lower end or edge as well as its end edges to the companion. Stitches *g*, running crosswise said piece and about the center thereof, binding the middle portion to the companion, provide two pockets *h* and *i* which are designed to receive a pen-wiper and rubber and the other a sponge. The upper edge *j*, of these pockets or receptacles has a binding which is also made of wa-

ter proof material. The bottom *k* thereof is bound with similar material.

D, indicates a similar strip of material as 55 that shown at C. The same is stitched around its edge to the companion as at *l l* and *m* and at its center at *n* to a point *o* about half way or the center of said strip or piece D, when said stitching runs laterally and to the edge 60 of the companion providing a pocket *p* for pens while the pocket *q*, is designed for a bottle containing water or inks as desired. A slit or space *r* is cut in the lower portion of the piece D, which gives access to the pocket 65 *s* or space below the pocket containing pens.

Between the lower edge of the piece C and the upper edge of the piece D, is left a space *t*, across which is arranged a piece of cloth or other material *u* and which is stitched at each 70 end *v, v*, to the companion, and said piece is designed to receive a ruler and hold it in position in the companion. The space *s*, or pocket is designed to receive an eraser or ordinary knife, and the slits or openings are 75 designed to protect the pencil points. On the back of the companion is a pocket *x*, which is to receive writing books, cards, &c. Strings *w w*, are connected to one end of the companion, or the outer fold and serve to tie up said 80 companion.

It will be seen that I construct a scholar's companion of water proof as well as flexible material, the same being noiseless with the most careless handling, the same containing 85 pockets for different articles, and the elastic holder in connection with the slits hold the pencils in place as well as protect the points thereof; cannot become accidentally displaced, and a device as herein shown and described is durable, handy to carry, and ornamental as well as cheap to manufacture.

Having thus described my invention, what I claim, and desire to secure by Letters Patent, is—

A scholar's companion formed of water proof material and having on its inner face a series of openings through which pass strips of elastic material, to receive pencils the ends of which enter openings formed in said inner face, the strip C, having opposite pockets one of which is adapted to receive a pen wiper and rubber, and the other a sponge, the strip D, forming separate pockets for pens and an

ink bottle, the pocket *s*, for the reception of a knife, the strip *u*, secured to the edges of the strips *C* and *D*, through which passes a ruler, and the pocket *x*, arranged on the outside or back of the companion, the whole combined and arranged as and for the purposes specified.

In testimony whereof I affix my signature in presence of two witnesses.

ABBIE E. GREVES.
